UNITED STATES PATENT OFFICE.

GEORGE HALM, OF NEW YORK, N. Y., ASSIGNOR TO DAVID WOLFE BRUCE, OF SAME PLACE.

DESIGN FOR TYPE.

SPECIFICATION forming part of Design No. 16,673, dated May 4, 1886.

Application filed April 3, 1886. Serial No. 197,718. Term of patent 14 years.

To all whom it may concern:

Be it known that I, GEORGE HALM, (assignor to DAVID WOLFE BRUCE,) of the city, county, and State of New York, have invented 5 a new and original Design for a Font of Printing-Type, of which the following is a specification.

The nature of my design is clearly shown in the accompanying typographic impression, to which reference is made; and it consists of an unshaded letter, the upper portion of which is heavier than the lower portion.

15 The base of the A, F, H, I, K, M, N, P, R, T, V, W, X, and Y is provided with the triangular ornament, as shown, and this ornamentation is found in the H, I, K, L, M, N, U, W, and Y at the top of the letters, and in the left-hand limb of the V and X. The B consists of 20 the up-and-down portion, from which extends, upon the right hand, the horizontal line, followed by the light curved line, and this by a second curved line extending from the base of the up-and-down portion and joining the upper curved line near its outer or right-hand boundary. The C consists of the curved line, as shown. The D consists of the up-and-down portion, followed upon the right by the horizontal line projecting from its upper portion, 25 and the rest of the letter formed of the curved line extending from the right termination of the horizontal line to the base of the up-and-down portion. The E resembles the C, and is provided with the central horizontal line. 30 In the H the central ornamentation consists of the two parallel lines. In the N the left-hand up-and-down portion is extended below the line. In the O the upper portion of the letter is divided, as shown, and a space left 35 in the same. The lower portion of the Q is looped upon the left, as shown. In the V and X the right-hand portion of the letters curls to the left, as shown. The left-hand and right portions of the W are extended above the 40 central portion. In the Y the left-hand upper portion of the letter crosses the upper part of the up-and-down portion; and the Z is formed of the horizontal line upon the left, followed by the line inclining downward from its right-hand termination, succeeded by the 50 curved line having the flourish upon its upper left-hand termination.

Certain of the letters, notably the C, E, G, and S, are ornamented by the lance-like figure, as shown in them at the upper right-hand 55 termination.

The character of the design is preserved in the symbol &, the punctuation-marks, numerals, dollar and pound-sterling marks, and in the lower-case. 60

Having now described my invention, I claim as new—

The design for a font of printing-type, as shown, the same consisting of an unshaded letter, the upper portion heavier than the 65 lower portion, the base of the A, F, H, I, K, M, N, P, R, T, V, W, X, and Y provided with the triangular ornament, as shown, and this ornamentation found in the H, I, K, L, M, N, U, W, and Y at the top of the letters, 70 and in the left-hand limb of the V and X, the B consisting of the up-and-down portion, from which extends, upon the right hand, the horizontal line, followed by the light curved line, and this by a second curved line 75 extending from the base of the up-and-down portion and joining the upper curved line near its outer or right-hand boundary, the C consisting of the curved line, the D consisting of the up-and-down portion, followed 80 upon the right by the horizontal line projecting from its upper portion, and the rest of the letter formed of the curved line extending from the right-hand termination of the horizontal line to the base of the up-and-down portion, the E resembling the C, and provided with the central horizontal line, the 85 H ornamented centrally by the two parallel lines, the left-hand up-and-down portion of the N extended below the line, the O having 90 its upper portion divided and a space left in the same, the lower portion of the Q looped upon the left, as shown, the right-hand upper portion of the V and X curling to the left, as shown, the left-hand and right-hand portions of the W extended above the central portion, the left-hand upper portion of the Y crossing the upper part of the up-and- 95 down portion, the Z consisting of a horizontal line upon the left, followed by a line inclining downward from its right-hand termination, succeeded by a curved line having a 5 flourish upon its upper left-hand termination, the C, E, G, and S ornamented by the lance-like figure, as shown, and the character of the design preserved in the symbol &, the punctuation-marks, the numerals, the dollar and pound-sterling marks, and the lower-case. 10
